BUSHING PULLER

Michael Claps, Denver, Colo., assignor to
Harry D. Owen, Denver, Colo.Continuation of application Serial No. 651,725,
March 4, 1946. This application July 16, 1948;
Serial No. 38,999.

1. Claim. (Cl. 29—263)

1.

This application is a continuation of my application Serial No. 651,725 filed March 4, 1946; now abandoned, for an improvement in bushing puller.

The invention relates to bushing pullers and more particularly to one which is well adapted for pulling blind bushings.

One of the objects of the invention is to produce a bushing puller which is simple and sturdy in construction, economical to manufacture and efficient in use.

Another object is to produce a bushing puller which does not employ expandible resilient pulling fingers, thus eliminating expensive material and manufacturing costs.

A further object is to produce a bushing puller which is provided with independent pulling elements that can be readily replaced at low cost in event of breakage or damage and thereby provide for a considerable savings over the purchase price of a complete new puller.

Other objects of my invention will become apparent from the following description taken in connection with the accompanying drawings showing a preferred bushing puller construction.

In the drawings:

Figure 1 is a perspective view of the bushing puller;

Figure 2 is a view of the puller with parts broken away and in section to show details of construction and manner of cooperation of the parts;

Figure 3 is a view of one of the pulling members; and

Figure 4 is a view showing the puller in readiness to pull a blind bushing.

Referring to the drawings in detail, it will be noted that my improved bushing puller comprises essentially four parts, namely, a rod or shaft 1, a nut or block 2 and two pulling members 3 and 4. The rod 1 is provided intermediate its ends with threads 5 and at its outer end has associated therewith a turning handle 6 in the form of a slidable cross rod. The inner end of the rod which is adapted to engage a suitable abutment is formed with a bevel 7, the purpose of which will become apparent.

The nut or block 2 is formed with a threaded bore 8 at its outer end which communicates with a larger smooth wall bore 9 at its inner end. The block or nut is arranged to be mounted by means of its threaded bore on the threads 5 of the rod.

The two bushing puller members 3 and 4 are of like construction, being of slightly less curva-

ture than a semicylinder. The radius of curvature of their outer surfaces is substantially the same as bore 9 of the nut and the radius of curvature of their inner surfaces is substantially the same as that of the rod. The inner ends of each of the bushing puller members are provided with outwardly extending flanges 10 and the outer ends, which are to fit within the bore 9 of the block or nut, are provided with a bayonet type of slot 11 having its open side extending to one edge of the member. These slots 11 are arranged to receive pins 12 carried by the block or nut. The pins are diametrically opposed to each other and the inner ends thereof extend into the bore 9 substantially the distance of the radial thickness of the pulling members 3 and 4. The size of the pins 12 is such that when the members 3 and 4 have the rod 5 received therebetween the pins can slide in the spaces between the adjacent longitudinal edges of the members and to a position where they can be received in the slots 11 by a relative movement between the members and the nut or block 2.

In using the improved bushing puller the two pulling members 3 and 4 are first inserted into the bushing 13 which, as shown in Figure 4, may be of the blind type and mounted in a bore of a support 14 such as a housing. Due to the fact that the pulling members 3 and 4 are of less curvature length than a semi-cylinder, they can be placed with their adjacent longitudinal edges in engagement so as to allow for the flanges 10 to pass through the bushing into the space at the inner end thereof. After the pulling members are inserted, the inner end portion of the rod 1 is inserted between the members and due to its size it thereby causes the members to be expanded so that the flanges 10 will assume positions where they can engage behind the inner end edge of the bushing as indicated in Figure 4. The beveled edge 7 at the inner end of the rod assists in inserting the rod in between the two pulling members. As the rod is inserted, the other ends of the pulling members will be received in the smooth large bore 9 of the nut or block and since the members 3 and 4 are now in their spaced apart positions, the pins 12 of the nut can be received in the space between the adjacent longitudinal edges of the members 3 and 4 and assume positions opposite the slots 11. The nut can then be twisted so that these pins 12 are moved into the slots to establish a connection between the nut and the pulling members 3 and 4. To pull the bushing all that need now be done is to turn the rod 1 so as to feed

it through the nut or block. The inner end of the rod will engage the end wall of the housing bore in which the bushing 13 is mounted and, consequently, as the rod is turned, the nut or block will be moved longitudinally outwardly with respect to the rod and pull with it the pulling members 3 and 4. Since the flanges 10 of these members are positioned behind the inner end edge of the bushing, the bushing will be pulled outwardly and thus be removed from the bore of the support. If the bushing to be pulled is in a bore open at both ends, a suitable abutment can be made for the beveled end of the rod to engage.

In connection with my improved bushing puller, it is to be particularly noted that it is very simple in construction and that the parts thereof can be easily and economically manufactured. I am aware that bushing pullers have been previously made, in which integral pulling members or fingers are carried by a nut or block similar to the nut or block 2, but in such type of puller the nut and fingers must be made of costly material in order that the fingers can be resiliently attached to the nut. Also, by having the pulling members 3 and 4 integral with the nut, the cost of manufacturing is considerably increased as many machining operations must be performed. By having the pulling elements 3 and 4 made separately from the nut, they can be readily replaced at a low cost in the event the pulling members become damaged or broken. The replacement cost will be considerably less than the cost of buying a complete new tool, or an integral nut and finger, as would be the case where the bushing puller was constructed with the nut and the pulling members made from one piece. The material for making my improved bushing puller need not be expensive, as there is no necessity for the pulling members to be resilient to permit expansion.

Being aware of the possibility of modifications in the particular bushing puller shown and described without departing from the fundamental principles of my invention, I desire it to be understood that the invention is not to be limited in any manner except in accordance with the appended claim.

What is claimed is:

In a puller for a bushing having a rear end edge free of any obstacle, said puller comprising two unitary independent elongated members

5 of semi-cylindrical shape provided at corresponding ends with shoulder means for engaging the rear end edge of the bushing to be pulled, a single rod of greater length than the members and having a uniform diameter portion for insertion between the members, said rod and members being so related that when said members are placed within a bushing with the shoulder means beyond the rear end edge of the bushing and the rod subsequently inserted between the members said members will be expanded uniformly throughout their length and the shoulder means will be held without wedging action so as to engage at the rear end edge of the bushing and the ends of the members opposite those with the shoulder means will be supported by the rod, a member threaded on the rod and having a cylindrical flange for surrounding said other end of the members to limit their expansion, and interengageable means comprising pins carried by the annular flange of the threaded member and slots in the sides of the independent elongated member for quickly connecting and disconnecting said members by relative turning movement of the threaded member with respect to the elongated members after the pins are inserted between spaced longitudinal edges of the said members and the single rod has been given a longitudinal movement inwardly relative to the elongated members to cause them to be expanded and held with their shoulder means positioned to engage the rear edge of the bushing, said pins being the sole connection of the elongated members and other parts of the bushing puller thus permitting easy hand removal.

MICHAEL CLAPS.
